Primary Examiner — Sandra S Snapp*Assistant Examiner* — Mehri F Bajoul(74) *Attorney, Agent, or Firm* — Pearne & Gordon LLP(57) **CLAIM**

The ornamental design for a ballistic presentation board, as shown and described.

DESCRIPTION

FIG. 1 is a back-right-top perspective view of a ballistic presentation board, showing our new design;

FIG. 2 is a top plan view thereof;

FIG. 3 is a bottom plan view thereof;

FIG. 4 is a right side elevational view thereof, the left side elevational view being a mirror image thereof;

FIG. 5 is a front elevational view thereof; and,

FIG. 6 is a back elevational view thereof.

The broken lines in the drawings represent unclaimed subject matter and form no part of the claimed design.

1 Claim, 2 Drawing Sheets(56)
